UNITED STATES PATENT OFFICE.

JOHN G. WHILLDIN, OF PHILADELPHIA, PENNSYLVANIA.

DESIGN FOR A FLOWER-POT.

SPECIFICATION forming part of Design No. 20,034, dated July 15, 1890.

Application filed June 21, 1890. Serial No. 356,304. Term of patent 14 years.

To all whom it may concern:

Be it known that I, JOHN G. WHILLDIN, a citizen of the United States, and a resident of Philadelphia, in the county of Philadelphia and State of Pennsylvania, have invented certain new and useful Designs for Flower-Pots; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a central vertical section. Fig. 2 is a bottom plan view.

This invention has relation to designs for flower-pots; and it consists in the novel form and configuration of parts, as hereinafter set forth.

In the accompanying drawings, the letter

A designates the body portion of the pot, which is in the form of a frustum of a cone, usually surrounded by a re-enforce or offset at its upper end, as at B, said body portion terminating below in the bottom C, having a diametrical groove *c* dividing its face into two segment-form lugs *g g*, as shown.

Having described this invention, what I claim as new, and desire to secure by Letters Patent, is—

The design for flower-pots, consisting of the conical body portion terminating below in the bottom C, consisting of the segment-form lugs separated by the diametrical groove *c*, as shown.

In testimony whereof I affix my signature in presence of two witnesses.

JOHN G. WHILLDIN.
